UNITED STATES PATENT OFFICE.

QUINCY A. BRACKETT, OF SPRINGFIELD, MASSACHUSETTS, ASSIGNOR TO WESTINGHOUSE ELECTRIC & MANUFACTURING COMPANY, A CORPORATION OF PENNSYLVANIA.

SIGNALING SYSTEM.

Application filed September 2, 1921. Serial No. 497,950.

To all whom it may concern:

Be it known that I, QUINCY A. BRACKETT, a citizen of the United States, and a resident of Springfield, in the county of Hampden and State of Massachusetts, have invented a new and useful Improvement in Signaling Systems, of which the following is a specification.

My invention relates to the control of high-frequency oscillations, and more particularly it relates to the control of high-frequency oscillations of an arc oscillator.

An object of my invention is to control the high-frequency oscillations of an arc oscillator without directly connecting the microphone or key within the supply circuit.

Another object of my invention is to provide means for controlling the high-frequency oscillations of an arc oscillator which will give complete control with great simplicity of apparatus, and which requires the handling of a small power by the key or microphone.

Hitherto, the control and modulation of high-frequency oscillations from an oscillating arc have usually been accomplished by controlling the radio-frequency circuit, as in the well known "compensated wave" and other similar methods. This has not proved altogether satisfactory, since often radiations were given out which, while not of the sending frequency, often caused wireless interference. Telephony has been

accomplished by inserting a microphone in the radio-frequency circuit, but as the microphone had to handle the entire power it has been possible to telephone only at low power.

The Poulsen-type arc will oscillate only if its supply current is substantially constant in value. This is usually accomplished by connecting the field-magnet coils used to extinguish the arc in series with the supply circuit. These field-magnet coils in practice are universally much larger and higher in energy-storing power than is necessary for the constant-current effect.

I so arrange the circuits that the field-magnet coils will not contribute to the constant-current effect in the arc supply. The direct-current source of supply for the arc will then have a constant-potential charac-

teristic with a minimum of constant-current characteristic. In the supply leads to the arc, I insert an inductive device, which I call a sustaining inductance, of approximately just sufficient size to give the minimum constant-current effect to enable the arc to generate high frequency oscillations. Associated inductively with this sustaining inductance is a controlling inductance located in a control circuit and so arranged that in signaling the constant-current effect of the sustaining inductance may be partially or entirely destroyed, thus stopping the arc oscillations or at least reducing the output.

I may employ a separately excited or shunt excited control circuit as desired. If under certain conditions of operation, the back E. M. F. generated by the variation of current in the sustaining inductance is objectionable, I may utilize an E-type core member so wound that the flux lines produced by the sustaining inductance cancel each other and produce a zero effect in the controlling inductance. The controlling inductance in this latter type operates to change the permeability of the core, which changes the value of the sustaining inductance, whereby the high-frequency output of the arc is varied. In other types, I may have the controlling inductance oppose the sustaining inductance to neutralize it and thereby reduce its effective value.

In the drawing:

Figure 1 is a diagrammatic view of a system embodying the principles of my invention.

Fig. 2 is a diagrammatic view of a modification of the system shown in Fig. 1.

In Fig. 1 I have shown a supply circuit comprising a direct-current generator 1 connected in series with a variable resistance 2, a sustaining induction coil 3, and electrodes 4 and 5 of an arc. The sustaining induction coil 3 is of such inductance that the constant-current effect produced is approximately a minimum for the operation of the arc as a generator of high-frequency current. This insures that there will be sufficient constant-current effect in the arc supply circuit to enable the arc to generate high-frequency oscillations, but at the same time, any diminution or change in the value

of the sustaining inductance of the coil 3 coil and the controlling induction coil. These will affect the high-frequency output of the arc.

The sustaining inductance coil 3 is wound upon an iron core 6 having an air gap 6^a. Likewise, wound upon the core 6 is a controlling induction coil 7, located in a shunt circuit which comprises the controlling induction coil 7 and a microphone 8. The controlling induction coil is wound to oppose the flux lines set up by the sustaining induction coil 3. The controlling induction coil 7 does not contribute to the constant current characteristic of the supply circuit and instead of having the circuit comprising the controlling induction coil 7 and the microphone 8, shunting the sustaining induction coil 3, I may, if desired, have the microphone circuit separately excited.

For de-ionizing the arc gap, I have provided arc magnets 9 and 11 comprising core members 12 and 13 wound with magnetizing coils 14 and 15, respectively. A direct-current generator 16, or any other suitable source of direct current keeps a constant, strong field between the arc magnets 9 and 11, whereby the arc gap between the electrodes 4 and 5 is quickly de-ionized, and the field may be adjusted to the best value by means of a variable resistor 16^a.

An oscillating circuit in which the high-frequency output of the arc may be utilized, comprises the arc electrodes 4 and 5, a condenser 17 and an induction coil 18.

Inductively coupled to the induction coil 18 in the oscillating circuit, is an induction coil 19 in an antenna circuit comprising an antenna 21, and, if desired, a variable condenser 22 through which the circuit is connected to the ground.

In operation, the generator 1 supplies current to the arc electrodes 4 and 5 through the sustaining induction coil 3 which is adjusted, as before stated, to give a sufficient constant-current effect to enable high-frequency oscillations to be set up in the oscillating circuit. The windings 14 and 15 of the arc magnets 9 and 11, respectively, are separately excited for the reason that it is desired that they shall not contribute to the constant-current effect. The amount of current flowing in the arc may be regulated by varying the variable resistance 2.

When speaking into the microphone 8, flux lines are set up in the core 6 by the controlling induction coil 7 in the microphone circuit. These flux lines oppose those set up by the sustaining induction coil 3 and the effective value of the sustaining induction coil 3 is reduced thereby. This affects the output of the oscillating arc. Therefore, the radiations given out by the antenna are impressed with voice vibrations.

In my system I have utilized an air-gap in the core for the sustaining induction

coil and the controlling induction coil. These coils may be interleaved or wound in any other desired fashion and the use of the air-gap is not necessary to the operation of my device. However, I prefer to employ an air-gap in the core because of the quick dying down in the flux upon a decrease in current, which is peculiar to the type of core.

It is to be understood that I may connect the circuit for exciting the arc magnets in shunt with the supply circuit, if desired; the sole purpose in showing them separately excited being to clearly indicate that the windings of the magnets do not contribute to the constant-current effect of the sustaining induction coil 3.

I have shown a system for controlling the output of an oscillating arc which does not require the use of control devices in the oscillating circuit, but which permits the speech modulation of the high-frequency output. In place of utilizing a microphone circuit, I may employ a key to effect control of current flow through the controlling induction coil.

In the modification shown in Figure 2, I have employed an E-type of core 23 having exterior legs 24 and an interior leg 25. As in the previous modification, I have shown this core as of the air-gap type to insure quick dying down of the flux upon release of the energy. Upon the exterior legs 24 of the E-type core 23 are wound sustaining induction coils 26, which are connected in such manner that the fluxes set up by them will oppose and neutralize one another in the central leg 25 of the core. Upon the central leg 25 is wound the controlling induction coil 27. The controlling induction coil 27 is comprised in a separately excited microphone circuit having a suitable source of direct current 28, which I have indicated as a battery, and a microphone transmitter 29.

The controlling inductance coil 27 operates to vary the permeability of the core 23. Upon speaking into the microphone 29, oscillations are set up in the controlling induction coil 27, which, by reason of the flux lines set up thereby, vary the permeability of the core 23.

The core 23 may be adjusted to operate near the knee of the saturation curve or near the low end of the curve, whereby large variations in the reactance of the sustaining induction coils 26 wound on the core 23 may be obtained. The induction coils 26, as in the case of the previously described modification, are adjusted close to the minimum value that will give the necessary constant-current characteristic for high-frequency oscillation of the arc. Therefore, a change in their effective reactance will cause variations in the arc output. Upon speaking into the microphone 29, oscillations are set up in

the controlling induction coil 27. The output of the arc is varied in accordance with the voice vibrations, since the permeability of the core 23 is varied in accordance with 5 the voice vibrations.

In this modification, I have shown an apparatus for controlling the reactance of the sustaining inductances in the supply circuit of the oscillating arc by varying the 10 permeability of the core upon which the sustaining inductance coils are wound.

Since I have not shown all the possible modifications of my invention that may occur to those skilled in the art, I desire that 15 my invention shall be limited solely by the appended claims and the scope of the prior art.

I claim as my invention:

1. A method of controlling the high-frequency output of an oscillating arc which 20 consists in changing the permeability of an iron core associated with an inductor in the supply circuit.

2. A method of controlling the high-frequency output of an oscillating arc which 25 consists in substantially saturating an iron core associated with an inductor in the supply circuit.

3. A method of controlling the high-frequency output of an oscillating arc having 30 an inductor of the cored type in its supply circuit which consists in opposing the flux lines set up in the core of the inductor.

4. A method of controlling the high-frequency output of an oscillating arc having 35 an inductor in its supply circuit which consists in opposing the flux lines set up by the inductor.

5. A system for controlling the high-frequency oscillations of an oscillating arc 40 comprising a supply circuit, a sustaining inductor in the supply circuit, an oscillating arc, an oscillating circuit and a controlling inductor the flux lines of which oppose 45 those of the sustaining inductor, whereby the high frequency output of the arc may be controlled.

6. A system for controlling the high-frequency oscillations of an oscillating arc 50 comprising a supply circuit, a sustaining inductor in the supply circuit, an oscillating arc, an oscillating circuit, a controlling inductor the flux lines of which oppose those 55 of the first mentioned inductor and a microphone connected to vary the current flow through the controlling inductor.

7. A system for controlling the high-frequency oscillations of an oscillating arc 60 comprising a supply circuit, a sustaining inductor in said supply circuit, an oscillating arc, an oscillating circuit and a controlling inductor in shunt with said sustaining inductor, the flux lines of said controlling inductor opposing those of said sustaining 65

inductor, whereby the high-frequency output of the arc may be controlled.

8. A system for controlling the high-frequency oscillations of an oscillating arc 70 comprising a supply circuit, a sustaining inductor in the supply circuit, an oscillating arc, an oscillating circuit, a controlling inductor in shunt with the sustaining inductor, the flux lines of the controlling inductor opposing those of the sustaining inductor, and a microphone connected to vary 75 the current flow through the controlling inductor.

9. A system for controlling the high-frequency oscillations of an oscillating arc 80 comprising a supply circuit, a sustaining inductor in the supply circuit, an oscillating arc, an oscillating circuit, a controlling inductor in shunt with the sustaining inductor, the flux lines of the controlling inductor opposing those of the sustaining inductor, and an air-gap core upon which said 85 inductors are wound.

10. A system for controlling the high-frequency oscillations of an oscillating arc 90 comprising a supply circuit, a sustaining inductor in the supply circuit, an oscillating arc, an oscillating circuit, a control inductor in shunt with the sustaining inductor, the flux lines of the control inductor opposing 95 those of the sustaining inductor, an air-gap core upon which said inductors are wound and a microphone connected to vary the current flow through the controlling inductor.

11. A system for controlling the high-frequency oscillations of an oscillating arc comprising a supply circuit, a sustaining inductor in the supply circuit, an oscillating arc, an oscillating circuit, a separately excited 100 magnetic field for said arc and a controlling inductor the flux lines of which oppose those of the sustaining inductor, whereby the high frequency output of the arc may be controlled.

12. A system for controlling the high-frequency oscillations of an oscillating arc comprising a supply circuit, a sustaining inductor in the supply circuit, an oscillating arc, an oscillating circuit, a magnetic field member for said arc, means for exciting said field member separately of said supply circuit, a controlling inductor in shunt which the sustaining inductor, an air-gap core upon which said inductors are wound and a microphone connected to vary 115 the current flow through the controlling inductance.

13. A system for controlling the high-frequency oscillations of an oscillating arc 120 comprising a supply circuit, a variable resistor in said supply circuit, a sustaining inductor in said supply circuit, an oscillating arc, an oscillating circuit, said sustaining inductor having approximately the 125

minimum value possible for high-frequency oscillations, a magnetic field member for said arc, means for exciting said field member independently of said supply circuit, a controlling inductor in inductive relation to the sustaining inductor and means for varying the current flow through the controlling inductor.

14. A system for controlling the high frequency oscillations of an oscillating arc comprising a supply circuit, a sustaining inductor in the supply circuit, an oscillating arc, an oscillating circuit, a core upon which the sustaining inductor is wound and a controlling inductor on said core for changing the permeability of the core, whereby the high-frequency output of the arc may be controlled.

15. A system for controlling the high-frequency oscillations of an oscillating arc comprising a supply circuit, a sustaining inductor in the supply circuit, an oscillating arc, an oscillating circuit, an iron core upon which the sustaining inductor is wound, a controlling inductor on said core for changing the permeability of the core and a microphone connected to vary the current flow through the controlling inductor.

16. A system for controlling the high-frequency oscillations of an oscillating arc comprising a supply circuit, a sustaining inductor in the supply circuit, an oscillating arc, an oscillating circuit, an iron core upon which the sustaining inductor is wound, and a separately excited controlling inductor on said core for varying the permeability of the core, whereby the high-frequency output of the arc may be controlled.

17. A system for controlling the high-frequency oscillations of an oscillating arc comprising a supply circuit, a sustaining inductor in the supply circuit, an oscillating arc, an oscillating circuit, an iron core upon which the sustaining inductor is wound, a

separately excited controlling inductor on said core for changing the permeability thereof and a microphone connected to vary the current flow through the sustaining inductor.

50

18. A system for controlling the high-frequency oscillations of an oscillating arc comprising a supply circuit, a sustaining inductor in the supply circuit, an oscillating arc, an oscillating circuit, an E-type core upon which the sustaining inductor is wound, and a controlling inductor on said core for changing the permeability of the core whereby the high-frequency output of the arc may be controlled.

60

19. A system for controlling the high-frequency oscillations of an oscillating arc comprising a supply circuit, a sustaining inductor in the supply circuit, an oscillating arc, a separately excited magnetic field for said arc, an oscillating circuit, an iron core upon which the sustaining inductor is wound and a controlling inductor on said core for changing the permeability of the core whereby the high-frequency output of the arc may be controlled.

65

20. A system for controlling the high-frequency oscillations of an oscillating arc comprising a supply circuit, a variable resistance in the supply circuit, an oscillating arc, an oscillating circuit, a sustaining inductor included in the supply circuit and having approximately the minimum value possible for high frequency oscillations in the oscillating circuit, an iron core upon which the sustaining inductor is wound and a controlling inductor on said core for changing the permeability of the core, whereby the high-frequency output of the arc may be controlled.
